UNITED STATES PATENT OFFICE.

LOUIS H. MAIER, OF NEW YORK, N. Y.

OPERATING MECHANISM FOR MUSIC-ROLLS.

1,146,436.

Specification of Letters Patent. Patented July 13, 1915.

Application filed May 29, 1912. Serial No. 700,417.

To all whom it may concern:

Be it known that I, LOUIS H. MAIER, a citizen of the United States, and resident of New York city, borough of the Bronx, in the county of New York and State of New York, have invented certain new and useful Improvements in Operating Mechanism for Music-Rolls, of which the following is a specification.

10 My invention relates to improvements in means for controlling the music sheets in automatic musical instruments, such as player pianos and the like, and has for its object to provide simplified music sheet controlling mechanism comprising means to apply a brake to the driving gear or wheel of the music sheet take-up roll or of the re-roll devices according to which is being operated, which brake is brought into action as 20 a handle is moved to cause the music sheet to be wound on the take-up roll or to be re-wound.

A further object of my invention is to provide improved means to control the flow 25 of air for operation of the music roll operating motor, and the flow of air to the note operating pneumatics of an automatic musical instrument, when the aforesaid handle is shifted from the playing to the re-rolling 30 position, and vice versa.

My invention comprises novel details of improvement and combinations of parts that will be more fully hereinafter set forth and then pointed out in the claims.

35 Reference is to be had to the accompanying drawings forming part hereof, wherein, Figure 1 is a partly sectional front elevation of music sheet controlling mechanism embodying my invention; Fig. 2 is an under side view of Fig. 1; Fig. 3 is an enlarged sectional view substantially on the line 3-3, in Fig. 1; Fig. 4 is a cross section of Fig. 3 on the line 4-4, in Fig. 3; Fig. 5 is an edge view of a portion of Fig. 3, and 40 Fig. 6 is a detail of a modification. Fig. 7 is a partly sectional detail view illustrating the connection of my improvements with motor and action controlling mechanism.

Similar numerals of reference indicate 45 corresponding parts in the several views.

The numeral 1 indicates a suitable tracker supported in any desired manner in a music roll box or the like 2, which may be installed in an automatic musical instrument in any well known manner. Said box or frame 2

is shown provided with shaft 3 to support music roll 4 and rewind the music sheet. 5 indicates suitable or well known means for removably supporting roll 4. The take-up roll 6 is supported by shafts 7, 8, in any well known manner. The parts above described may be of any well known or approved construction and form no part of my present invention. 60

10 indicates a driving shaft for the music sheet mechanism, and it is shown provided with a drive sprocket 11 to be driven by chain 12 from a motor in any well known manner. Shaft 10 carries a pinion 13 shown provided with a pin 14, which pinion is 65 adapted to mesh with a gear 15 secured on shaft 7 for rotating the takeup roll 6. Shaft 10 is mounted in bearings for sliding as well as rotary motion, and is shown provided with a grooved hub or the like 16 receiving 70 a fork or finger 17 for shifting said shaft. The fork or finger 17 is shown provided with a bent portion 17^a receiving the groove of hub 16, and said finger is shown journaled at 18 in base board 2^a of the music 75 box. Finger 17 is shown provided with a crank 19 pivotally connected by a link 20 with an eccentric or arm 21 carried by a shaft 22 of handle 23, which shaft is shown journaled in board 2^a, whereby when said 80 handle is shifted from the playing position shown in Fig. 1 to the re-roll position shown in Fig. 3, shaft 10 will be moved in an appropriate direction, and vice versa. Shaft 85 10 is shown mounted to slide in a bore in a bearing or sleeve 24 secured in a bushing 25 fitted firmly to the side wall 2^a of box 2, bushing 25 preferably being secured to or formed on a plate 26 shown secured to the wall 2^a by a screw and slot connection 27 90 (Fig. 4), and said plate 26 has a hub 26' serving as a guide for the hub of sprocket wheel 28. Bearing or sleeve 24 has a flange 24' located on the outer side of sprocket wheel 28, whereby the latter is journaled 95 upon bearing or sleeve 24 for independent rotation thereon, and is maintained in proper position by flanges 26', 24'. Bearing 24 is shown held in position by screw 29, Fig. 1. The parts may be assembled by 100 first applying bushing 25 upon wall 2^a, then passing bearing 24 through wheel 28, inserting said bearing in bushing 25, and securing the latter in proper position by screw 29, and then shaft 10 may be placed in bear- 105

110

ing 24. By this means bearing 24 independently supports shaft 10 and wheel 28. Upon wheel 28 is a pin 30 adapted to be engaged by pin 14 when pinion 13 is shifted 5 from gear 15 (Fig. 1) to the position shown in Figs. 4 and 5 for re-rolling the music sheet. A chain 31 passing over sprocket wheel 28 also passes over a sprocket wheel 32 on shaft 3 to rotate the latter and re-roll 10 the music sheet on roll 4. Between wheels 15 and 28 I provide a double-acting brake 33 adapted to engage wheel 15 or wheel 28 according to the position to which said brake 15 is shifted, but not to engage both of said

Brake 33 is shown carried by a vertically pivoted shaft 34 journaled in suitable bearings 35 on base 2^a, shaft 34 being shown bent laterally at 34^a, upon which lateral part the 20 brake 33 is carried, so that as said shaft is rocked the brake pads 33^a will be pressed against wheel 15 or wheel 28. Brake 33 is normally spring pressed toward wheel 28, for which purpose I have shown a spring 35 25 beneath and secured to base 2^a and connected with an arm 36 secured at the lower end of shaft 34, whereby brake 33 will be applied to wheel 28 to retard it when handle 23 is in the playing position, Fig. 1, thereby 30 releasing the brake from the takeup roll driving gear 15. When handle 23 is shifted to the rerolling position brake 33 is to be moved from wheel 28 into engagement with wheel 15 to retard the rotation of the latter. 35 For this purpose I have shown shaft 34 bent downwardly at 34^b (Fig. 4) and provided with a hole 37 (Fig. 3) receiving the end portion 38^c of a spring 38, the bent end 38^c of which spring is adapted to engage shaft 40 part 34^b near the end of the movement of handle 23 to the re-roll position, so that 45 brake 33 will be pulled and held against wheel 15 by spring action. Spring 38 is shown connected with an arm 39 secured to shaft 17, whereby as said shaft is rotated to cause the pinion to shift from engagement with gear 15 (releasing pin 14 from pin 20), and the tension of spring 38 is removed from arm 34^b, the spring 35 will rock shaft 34 50 to move brake 33 from engagement with wheel 15 into engagement with wheel 28. It will be understood from the foregoing that when handle 23 is in the playing position the brake is applied to wheel 28 to retard 55 the latter from rotation and permit free rotation of the take-up-roll driving gear 15, and that when handle 23 is shifted to the reroll position the brake is removed from the 60 reroll driving wheel 28 (to permit pin 14 acting upon pin 20 to freely rotate the latter and wheel 28 to reroll the music sheet on roll 4), and applied to the takeup roll driving gear 15 to retard the excessive rotation of the latter.

65 While in Figs. 1 to 5 I have shown pinion

13 adapted to be shifted from gear 15 and to be shifted back to said gear, whereby pin 14 is carried into and out of operative relation to pin 20, I have, in Fig. 6, shown means whereby pinion 13 may remain in 70 mesh with gear 15 whether it is being driven by shaft 15 or not. To this end pinion 13 is shown provided with flanges 13^a on opposite sides of gear 15, and shaft 10 slides freely through pinion 13 and is to be connected therewith to rotate the latter, and upon shaft 10 is secured a pin or projection 10^a adapted to engage either pin 14 of pinion 13 or pin 30 of sprocket wheel 28. A fork or guide 13^b retains pinion 13 in normal position at all times permitting shaft 10 to be shifted relatively to said pinion. The arrangement shown in Fig. 6 is such that when shaft 10 is shifted to the left in Fig. 6 pin 10^a will engage pin 30 to rotate 85 reroll driving wheel 28 and brake 33 will be in engagement with gear 15, and when shaft 10 is shifted to the right, pin 10^a will leave pin 30 and engage pin 14 to thereby rotate pinion 13 and gear 15, brake 33 then 90 being shifted against wheel 28. The result is the same as previously described except that pinion 13 remains in engagement with gear 15 instead of being shifted out of engagement therewith.

95 It is desirable when handle 23 is in the reroll position to permit air to flow to a suitable motor controlling mechanism 50, of any well known construction, and simultaneously to control the flow of air to the 100 note operating pneumatics. For this purpose, I have shown a pipe 40 connected with a block 41 secured on base 2^a and having a port 40^a controlled by a valve 42 which may be carried by a spring 42^a secured upon 105 block 41, as at 43. Valve spring 42^a is adapted to bear against eccentric 21, the arrangement being such that when handle 23 is in the playing position (Figs. 1 and 2) valve 42 will close port 40^a and prevent the 110 flow of air through pipe 40 to said motor controlling mechanism 50 and to the usual controlling mechanism 51 for the air of the pneumatic player mechanism, but when handle 23 is turned to the reroll position, eccentric 21 will push spring 42^a away and open port 40^a, as in dotted lines in Fig. 2, thereby permitting air to flow through pipe 40 to said motor controlling mechanism and to the controlling mechanism for the air 115 of the pneumatic player mechanism. The effect of flushing through pipe 40 allows full communication between the motor and the pumping apparatus to permit full motor speed for re-rolling, and simultaneously 120 breaks communication between the player action pneumatic chests and the pumping mechanism in order to avoid operation of the note pneumatic when re-rolling the 125 music sheet. As indicated in Fig. 7 the pipe 130

52 leads to the source of exhaust supply and pipe 53 leads to any suitable motor for operating chain 12, in a well known manner.

Changes may be made in the details of 5 construction and arrangements of parts set forth within the scope of the appended claims, without departing from the spirit of the invention.

Having now described my invention what 10 I claim is:

1. The combination of means for rotatively supporting a music sheet roll and a take-up roll, gearing for rotating the take-up roll, gearing for rotating the music roll, 15 means to cause rotation of one of said rolls at will, a brake interposed between said gearings to engage either of said gearings, and means to move the brake into operative action with one member of said gearings 20 and simultaneously shift the driving means to another member of said gearings.

2. The combination of means for rotatively supporting a music roll and a takeup roll, a driving wheel for the take-up roll, a 25 driving wheel to rewind the music roll, means to rotate either of said wheels at will, a brake interposed between said wheels, and means for shifting said brake from one of 30 said wheels into coaction with the other of said wheels and simultaneously shifting the driving means from the last wheel to the other driving wheel.

3. The combination of means for rotatively supporting a music roll and takeup 35 roll, a driving wheel for the takeup roll, a driving wheel for the music roll to rewind the latter, a pinion adapted to mesh with the first named driving wheel, a shaft carrying said pinion, a pin connected with said shaft, a pin connected with the second named driving wheel, means to shift said shaft to cause the first named pin to engage the second named pin to rotate the second named driving wheel, means to cause said 40 pinion to rotate the first named wheel when said pins are not in engagement and a brake interposed between said wheels to engage either of them.

4. The combination of means for rotatively supporting a music roll and a take-up roll, a driving wheel for the take-up roll, a driving wheel for the music roll to rewind the latter, a pinion adapted to mesh with the first named driving wheel, a shaft carrying said pinion, a pin connected with said shaft, a pin connected with the second named driving wheel, means to shift said shaft to cause the first named pin to engage the second named pin to rotate the second named driving wheel, means to cause said pinion to rotate the first named wheel when said pins are not in engagement, a brake between said wheels, and means to shift said brake into coaction with the first named wheel when said pins are in co-operative relation.

5. The combination of means for movably supporting a music roll and a take-up roll, a driving wheel for the take-up roll, a driving wheel for rewinding the music roll, means rotatively supporting the last named 70 wheel, a shaft slidable in the support for said wheel, a pinion carried by said shaft to drive the first named wheel, a pin carried by said shaft, a pin connected with the second named wheel to coact with the first 75 named pin, and means to shift said shaft to cause either of said driving wheels to rotate.

6. The combination of means for movably supporting a music roll and a take-up roll, a driving wheel for the take-up roll, a driving wheel for rewinding the music roll, means rotatively supporting the last named 80 wheel, a shaft slidable in the support for said wheel, a pinion carried by said shaft to drive the first named wheel, a pin carried 85 by said shaft, a pin connected with the second named wheel to coact with the first named pin, a grooved hub on said shaft, a rocking finger engaging the groove to operate said hub, a handle, and means connecting said handle with said finger for shifting said shaft.

7. The combination of means for movably supporting a music roll and a take-up roll, a driving wheel for the take-up roll, a driving wheel for rewinding the music roll, means rotatively supporting the last named 95 wheel, a shaft slidable in the support for said wheel, a pinion carried by said shaft to drive the first named wheel, a pin carried 100 by said shaft, a pin connected with the second named wheel to coact with the first named pin, a grooved hub on said shaft, a rocking finger engaging the groove to operate said hub, a handle, means connecting 105 said handle with said finger for shifting said shaft, a brake to coact with said drive wheels, a spring normally moving said brake toward one of said wheels, and a spring connected with said finger and with said brake 110 to move said brake into coaction with the other of said wheels.

8. The combination of means for movably supporting a music roll, and a take-up roll, a driving wheel for the take-up roll, a driving wheel for rewinding the music roll, means rotatively supporting the last named 115 wheel, a shaft slidable in the support for said wheel, a pinion carried by said shaft to drive the first named wheel, a pin carried by 120 said shaft, a pin connected with the second named wheel to coact with the first named pin, a grooved hub on said shaft, a rocking finger engaging the groove to operate said hub, a handle, means connecting said handle with said finger for shifting said shaft, a brake to coact with said drive wheels successively, a spring normally moving said 125 brake toward one of said wheels, and a spring connected with said finger and with 130

said brake to move said brake into coaction with the other of said wheels, said spring having independent play for a suitable distance between said finger and said brake.

9. The combination of means for movably supporting a music roll and a take-up roll, a driving wheel for the take-up roll, a driving wheel for rewinding the music roll, a bearing upon which the last named wheel is rotatively mounted, said bearing having a bore, a shaft slidable and rotative in said bore, said shaft having means to rotate either of said driving wheels at will, and means to shift said shaft longitudinally.

10. The combination of means for movably supporting a music roll, and a take-up roll, a driving wheel for the take-up roll, a driving wheel for rewinding the music roll, a bearing upon which the last named wheel is rotatively mounted, said bearing having a bore, a shaft slidable and rotative in said bore, said shaft having means to rotate either of said driving wheels at will, and means to shift said shaft longitudinally, said bearing having a flange at its outer end to retain said wheel on said bearing.

11. The combination of means for movably supporting a music roll and a take-up roll, a driving wheel for the take-up roll, a

driving wheel for rewinding the music roll, 30 a bearing upon which the last named wheel is rotatively mounted, a bushing supporting said bearing and having a hub to guide said wheel, said bearing having a flange without said wheel to guide the latter, said bearing 35 having a bore, a shaft slidable and rotative in said bore, said shaft having means to rotate either of said driving wheels at will, and means to shift said shaft longitudinally.

12. The combination of means for movably supporting a music roll and a takeup roll, a driving wheel for rewinding the music roll, a shaft provided with means to operate either of said wheels at will, a finger to shift said shaft, a handle, means connecting said handle with said finger to actuate the latter, a pipe having a port, a valve to control said port, said handle having an eccentric, and a spring connected with said valve and coacting with said eccentric to open and close said port.

Signed at New York city, in the county of New York, and State of New York, this 28th day of May, A. D. 1912.
